UNITED STATES PATENT OFFICE.

ELMER McCLELLAN AFRICA, OF HUNTINGDON, PENNSYLVANIA, AND BARTHOLOMEW E. McSHEEHY, OF NUTLEY, NEW JERSEY, ASSIGNORS TO J. C. BLAIR COMPANY, OF HUNTINGDON, PENNSYLVANIA, A CORPORATION OF PENNSYLVANIA.

WRITING-TABLET.

1,032,725.

Specification of Letters Patent. Patented July 16, 1912.

Original application filed January 18, 1908, Serial No. 411,445. Divided and this application filed May 2, 1908. Serial No. 430,619.

To all whom it may concern:

Be it known that we, ELMER McCLELLAN AFRICA, a citizen of the United States, and a resident of Huntingdon, in the county of Huntingdon and State of Pennsylvania, and BARTHOLOMEW E. McSHEEHY, a citizen of the United States, and a resident of Nutley, in the county of Essex and State of New Jersey, have invented certain new and useful Improvements in Writing-Tablets, of which the following is a specification.

This application is a division of our application No. 411,445, filed January 18, 1908.

15 This invention relates to tablets or pads of writing paper, and aims to provide certain improvements therein.

It has heretofore been proposed to supply with each tablet or pad a guide sheet having 20 guide lines ruled transversely of the pad. Such guide sheet has been useful only in using the paper in its full length condition without folding.

According to our present invention we 25 provide guiding means which are adapted to be conveniently utilized in connection with the paper sheets either when the latter are used lengthwise in various sizes for commercial letter writing, etc., or when they 30 are folded for social letter writing in various sizes.

According to the present invention we provide a guide sheet which is substantially 35 the same size as the writing sheets composing the tablet, and which is preferably attached to the tablet near the end of one side thereof. The guide sheet is preferably composed of two sections which are hinged together so that one part may fold over the 40 other. Preferably the sheet is constructed in one piece and creased to form the hinge joint.

By our invention at least three sides of 45 the writing sheet can be written upon with the assistance of the guide, without detaching the writing sheet from its connection with the tablet. The guide sheet is also applicable for use in connection with the fourth side of the writing sheet when the 50 latter is detached.

According to our invention in its preferred form the guide sheet is provided with longitudinal and transverse guide lines

on its upper side, and longitudinal guide lines on at least a part of its under side. 55 Instead of providing the guide sheet with ruled lines, it may be provided with any other suitable designs.

The invention also includes other features of novelty which will be hereinafter referred to.

Referring to the drawings illustrating an embodiment of the invention, Figure 1 is a perspective view of a tablet having our improved guide sheet connected therewith; 65 Fig. 2 is a plan view of Fig. 1 on a larger scale; Figs. 3, 4 and 5 are views illustrating the positions of the parts when writing upon four sides of a folded writing sheet. Fig. 6 is a view of one form of our improved guide sheet detached.

Referring to the drawings, let A designate the tablet as a whole which is shown as composed of a number of elongated sheets *a* connected along one of the short 75 sides of the tablet at *b*. Preferably a back-board *c* is provided as is common, and a cover *d* which is shown as connected to the tablet at its binding edge, or that edge at which the sheets are attached in the form 80 shown. Preferably the dimensions of the tablet are such that when the sheets are folded along the dotted line *e* (Fig. 1) the lower edge will meet the top edge, so that the paper assumes the proper form for correspondence, etc. 85

B indicates our improved guide sheet, which is of substantially the same dimensions as the letter sheets of the tablet. It is composed of two parts *B'* *B''* which are 90 hinged together as shown, so that one of such parts may turn completely over upon the other. By preference the sheet is formed of a single piece of paste board or other material which is creased along the line *x* to 95 provide the necessary hinge joint. Preferably the guide sheet *B* is hinged to the tablet at one of the sides of the latter by means of a strip of paper or canvas *f* which is glued to the back-board *c* and to the under side of 100 the guide sheet *B*. The hinge *f* does not extend the entire length of the tablet, but only the width of the part *B''* of the guide sheet, so that the part *B'* is left free to fold over on the part *B''*. The hinge *f* is preferably 105 stiff laterally, so that when the guide sheet

is folded over upon the top of the tablet it rests securely thereon with its lines parallel to the edges of the tablet and does not move from side to side in use.

5 When the guide sheet B is used to provide writing lines, it is preferably ruled lengthwise with lines g and transversely with lines h on its upper side, so that when the guide sheet is placed beneath the uppermost writing sheet, the latter may be written upon either longitudinally or transversely as desired. Preferably the lower half B' of the guide sheet is provided on its under side with lines g^2 which extend longitudinally of the tablet, and such lines may also be continued upon the under side of the upper half B^2 if desired. Both sides of the guide sheet may also be provided with one or more lines h' , h^2 , which extend transversely of the tablet for a purpose to be described.

In the use of the tablet when the writing sheet is to be folded to correspondence size, the guide sheet is brought down over the 25 face of the tablet, and the upper writing sheet of the latter is folded with the portion B' over upon the portion B^2 of the sheet. During this movement the hinge joint between the two halves of the guide sheet 30 serves as a guide for folding the writing sheet. When the latter is folded, the first page of the writing sheet lies in proper position for writing with the under side of the part B' of the guide sheet immediately beneath it. During writing the transverse line h' may be used to indicate the proper margin at the left hand side of the sheet. Instead of one line h' any number may be used, so that the margin may be varied at will. A 40 line h^2 may also be provided to form a guide on the opposite side.

After the first page of the writing sheet is written upon, the parts are restored to their original position and the entire sheet lifted, 45 so that the guide sheet may be passed beneath it into the position shown in Fig. 4. In this position the second and third pages of the writing sheet are brought into place for use. When the third page is completed, 50 if it is desired to utilize the fourth page, the guide sheet with the writing sheet is swung outwardly, thereby detaching the writing sheet from the tablet. As the fold in the writing sheet is still preserved, it is easily 55 slipped over the upper part B' of the guide sheet with the fourth page in position for writing. During the operation of writing upon the second, third and fourth pages, any of the lines h , h' , h^2 may serve as marginal guide lines. It is, of course, within 60 this feature of the invention, however, to omit all of the transverse lines h with the exception of those which are intended to serve as marginal guides. We prefer, however, to provide a complete set of transverse 65

lines h , since these are very desirable in case it is required to use the full length writing sheet without folding. For this purpose the guide B is slipped beneath the writing sheet in a well known manner.

According to our invention we may form the guide sheet B of blotting paper, although it may be made of any other suitable material, as hereinbefore described. When the guide sheet is incorporated in a tablet, a 75 separate blotting sheet n is preferably provided, as shown in Fig. 1, wherein it is illustrated as attached to the under side of the cover.

By the present invention the use of correspondence paper in tablet form is greatly facilitated. The guide sheet B folds down accurately upon the writing sheets without detaching the latter, so that such sheets are practically held in position without any effort on the part of the user. The guide sheet is immediately available for all of the pages of the writing sheet, and renders the use of the tablet extremely convenient.

It will be understood that while the sheet 90 B is preferably attached to the tablet, it may be detached therefrom and still be very useful in connection with tablets or other writing paper. In Fig. 7 we have illustrated the sheet B detached. Such guide sheet can 95 be very cheaply manufactured, there being but little difference between its cost and that of the guide sheets now in common use.

It is obvious that various modifications may be made in the construction herein 100 shown without departing from the spirit of the invention.

What we claim is:—

1. A tablet having a plurality of paper sheets connected together at an edge thereof, 105 and said tablet having a sheet having guiding provisions visible through one of such paper sheets when the guide sheet is placed beneath it, said guide sheet comprising two portions connected by a foldable joint, one of said portions being connected to a side of the tablet other than the connecting edge of said paper sheets.

2. A tablet having a plurality of paper sheets connected together at an edge thereof, 115 and said tablet having a sheet having guiding provisions visible through one of such paper sheets when the guide sheet is placed beneath it, said guide sheet having a portion only of one of its edges connected to a side 120 of the tablet other than the connecting edge of said paper sheets, and said guiding provisions comprising guide lines extending parallel to the side of the tablet to which said guide sheet is attached.

3. A tablet having a plurality of paper sheets connected together at an edge thereof, 125 and said tablet having a sheet having guiding provisions visible through one of such paper sheets when the guide sheet is placed 130

beneath it, said guide sheet comprising two portions connected by a foldable joint, one of said portions being connected to a side of the tablet other than the connecting edge of 5 said paper sheets, and said guiding provisions comprising guide lines extending at right angles to said joint and located on the upper and lower faces of the sheet.

4. A tablet having a plurality of paper 10 sheets connected together at an edge thereof, and said tablet having a sheet having guiding provisions visible through one of such paper sheets when the guide sheet is placed beneath it, said guide sheet comprising two 15 portions connected by a foldable joint, one of said portions being connected to a side of the tablet other than the connecting edge of said paper sheets, and said guiding provisions comprising guide lines extending at 20 right angles to said joint and located on the upper and lower faces of the sheet, and guide lines extending transversely to the first and located on one of the faces of the sheet.

25 5. A tablet having a plurality of elongated paper sheets connected together at one of the short sides thereof, and said tablet having a sheet having guiding provisions visible through one of such paper sheets 30 when the guide sheet is placed beneath it, said guide sheet having a foldable joint at its middle and having one of its portions only connected to said tablet at one of the long sides of the latter.

35 6. A tablet having a plurality of elongated paper sheets connected together at one of the short sides thereof, and said tablet having a sheet having guiding provisions visible through one of such paper sheets 40 when the guide sheet is placed beneath it, said guide sheet having a foldable joint at its middle and having one of its portions only connected to said tablet at one of the long sides of the latter, and said guiding 45 provisions comprising guide lines extending longitudinally of the tablet.

7. The combination with a tablet having a series of flat writing sheets bound along an edge, of a guide sheet of substantially the 50 same length and breadth when flat as said

writing sheets, and adapted to be inserted flat beneath the top writing sheet to form a guide sheet for substantially the entire writing sheet, said guide sheet being creased crosswise of its length and having longitudinal and transverse guide lines extending substantially entirely over one side, and longitudinal guide lines on its other side so that the writing may be guided on at least three sides of the writing sheets without detaching the latter from the body of the tablet.

55 8. The combination with a tablet having a series of flat writing sheets bound along an edge, of a guide sheet of substantially the same length and breadth when flat as said writing sheets, and adapted to be inserted flat beneath the top writing sheet to form a guide sheet for substantially the entire writing sheet, said guide sheet being creased crosswise of its length and having longitudinal guide lines on both sides and marginal transverse lines on both sides.

60 9. The combination with a tablet having a series of flat writing sheets bound along an edge, of a guide sheet of substantially the same length and breadth when flat as said writing sheets, and adapted to be inserted flat beneath the top writing sheet to form a guide sheet for substantially the entire writing sheet, said guide sheet being creased crosswise of its length and having longitudinal guide lines extending substantially entirely over one side and marginal transverse lines thereon, and having longitudinal guide lines extending across one-half of its other side and marginal guide lines thereon.

65 In witness whereof, we have hereunto signed our names in the presence of two 70 subscribing witnesses.
